JESSE A. B. SMITH, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,152,856.

Specification of Letters Patent. Patented Sept. 7, 1915.

Application filed May 20, 1914. Serial No. 839,667.

To all whom it may concern:

Be it known that I, JESSE A. B. SMITH, a citizen of the United States, residing in Brooklyn borough, in the county of Kings, city and State of New York, have invented certain new and useful Improvements in Type-Writing Machines, of which the following is a specification.

This invention relates to attachments for typewriting machines, particularly adapted to facilitate the rapid and accurate placing of work-sheets on the machine in position to be written upon. The attachment may be in the form of a paper table and guide 10 adapted to be placed over the usual paper shelf at the intake side of the platen, the attachment extending forwardly beneath the platen and spaced therefrom to permit work-sheets placed upon said guide to be slipped 15 forward around the platen to writing position.

The attachment may comprise side flanges forming gages for the side edges of the work-pieces, said flanges having curved extensions 20 beneath the platen of sufficient depth to properly space the guide from the platen. Arms which may be either rigidly secured to or hinged to said side flanges, may extend over the platen and around to 25 meet the paper shelf beneath the platen, said arms serving to position and support the attachment on the platen, and also guide the work-sheets over the printing line. By hinging said arms, they may be lifted to 30 permit the attachment to be quickly removed from the machine without removing the platen.

The attachment may be adjustably secured to a rod behind the paper shelf and 40 extending longitudinally of the platen, the attachment having a slidable connection with said rod whereby it may be adjusted to any position along the platen. The work-sheet, when in position, may be held to the 45 platen and fed forward by means of feed rolls, which may be thrown off the platen to permit the work-sheet to be positioned.

Other features and advantages will hereinafter appear.

50 In the accompanying drawings, Figure 1 is a sectional perspective view of the attachment applied to the platen of an Underwood typewriting machine. Fig. 2 is an end view of a slightly modified form of the attachment, the guide arms which extend over the

platens being in this case rigid with the attachment. Fig. 3 is a perspective view of one of the hinged guide arms shown in Fig. 1. Fig. 4 is a sectional elevation view showing the parts in normal position. Fig. 5 is 60 a view showing the method of removing the attachment from the machine, the attachment being disconnected and thrown forward.

A rotary platen 1 is fixed to an axle 2, 65 journaled in a platen frame 3. Type-bars 4 carrying upper and lower case types 5, may be operated in the usual manner to throw them upwardly and rearwardly against the front face of the platen for printing on the 70 work-sheet. The platen frame may comprise the usual inclined paper shelf 6 at the rear of the platen, said shelf connecting the ends of the platen.

The attachment embodied in the present 75 invention comprises an inclined table 7 placed over the shelf 6, the lower end of said table being curved to extend forward beneath the platen concentrically with the platen. Side flanges 8 on said table serve as 80 gages for the lateral edges of the work-sheets, and the lower portions 9 of said gages are reduced in width and curved to conform to the surface of the platen, the width of the extensions 9 being just sufficient to hold the 85 curved portion of the table 7 a short distance from the platen, leaving a narrow passageway 10 through which a work-sheet placed on the table 7 may be slipped forward into position to be written upon. Lat- 90 eral guide arms 11 connected by pivots 12 to the flanges 8 extend forwardly over the platen and curve downwardly to meet the exten- 95 sions 13 at the forward end of the table 7. The attachment thus completely surrounds the platen. The arms 11 may have inwardly extended flanges or projections 14 which serve to guide the work-sheet over the front face of the platen and direct it backwardly over the platen. Said arms 11 serve to 100 guide the sheet laterally until the final line is written thereon. The arms 11 further serve to hold the attachment accurately positioned with respect to the platen.

The upper end of the table 7 may be bent 105 to a horizontal position, and rest upon the bead or rolled end 15 of the shelf 6, and is secured by thumb screws 16 to brackets 17 slidably mounted for longitudinal adjustment on a horizontal rod 18 located behind 110

the shelf 6 and secured to the platen frame in any suitable manner, as, for example, by arms 19 attached to the rear face of the shelf 6. The brackets 17 may be frictionally held in adjusted position on the rod 18 by leaf springs 20, which bear against pins 21 carried by the brackets and seated in a groove 22 extending along the upper surface of the rod 18. Thus the entire attachment 10 may be adjusted along the platen, and the guides 9 and 11 may clasp the platen closely so as to prevent sheets from slipping between said guides and the platen.

The attachment may be removed from the machine by loosening the thumb screws 16 and swinging the arms 11 rearwardly about their pivots 12, and then swinging the attachment forward to the Fig. 5 position, when it is free to be lifted from the machine.

20 The guide arms 11 may be held in normal position by springs 23, each attached at its upper end to a pin 24 on the arm 11, and at its lower end to a pin 25 on the flange 8, the pin 25 also serving as a stop for said arm. The springs 23 also serve to hold the arms 11 when thrown back to the Fig. 5 position, the movement of said arms about their pivots being limited in such direction by a stop pin 26.

30 In the modified form shown in Fig. 2, the arms 11 are integral with or rigidly connected at 27 to the flanges 8. When a bill or other work-sheet has been placed on the table 7 and slipped forward between the platen and the table 7 to printing position, it is held in such position and fed forwardly over the platen by feed rolls 28, which may be located just forward of the front edge of the table 7. These rolls are mounted on a 40 shaft 29 as supported in levers 30 journaled on a tie-rod 31 extending between the ends of the platen frame. The rolls are lifted from the platen by means of a finger-key 32 connected through a link 33 to an arm 34 45 on a rock shaft 35 provided with flats 36 in engagement with arms 37 of the levers 30. When the finger-key 32 is depressed, the shaft 35 is rocked and lifts the feed rolls 28 from the platen, permitting a work-piece to be placed on the platen or removed independently of the rotation of the platen. When the finger-key 32 is again lifted, the rolls 28 are returned to the platen.

55 Variations may be resorted to within the scope of the invention, and portions of the improvements may be used without others.

Having thus described my invention, I claim:

1. An attachment for typewriting machines, comprising a paper table having a 60 curved portion to extend partially around the platen, means to hold said curved portion spaced from the platen, and guide arms extending from said table around the opposite side of the platen to meet said table and

thereby surround the platen, said arms provided with guides for the work-sheet spaced from the platen.

2. The combination with a rotary platen, of a stationary table forming a guide for 70 work-pieces, said guide curved around the platen and spaced a short distance therefrom to permit a work-piece to be slipped into position between the platen and said guide, and arms secured to said guide and extending around the platen on the opposite side from said curved portion to hold the attachment in position on the platen.

3. The combination with a rotary platen, of a stationary table forming a guide for 80 work-pieces, said guide curved around the platen and spaced a short distance therefrom to permit a work-piece to be slipped into position between the platen and said guide, and arms secured to said guide and 85 extending around the platen on the opposite side from said curved portion to hold the attachment in position on the platen, said arms hinged to the guide and movable into position to permit the removal of said guide 90 from the platen without removing the platen from the machine.

4. The combination with a rotary platen, of a rear stationary guide for work-sheets 95 curved around under the platen and spaced therefrom to permit a work-sheet to be slipped between the platen and said guide, and having means to guide the side edges of the work, and guiding arms secured to said guide in rear of the platen and extending forwardly over the platen and across the printing line, said arms also provided with means for guiding the work-sheet laterally.

5. In a typewriting machine, the combination with a platen frame and platen, said frame comprising a paper shelf at the rear of the platen, of an auxiliary paper table supported on said shelf and extending forward beneath the platen and spaced therefrom to permit a work-sheet to be slipped between said table and platen, said table provided with side flanges having curved extensions to hold the said table spaced from the platen, arms pivoted to said flanges and extending forward over the platen and curved around the platen toward said table, said arms having inwardly-extended flanges spaced from the platen to guide the side edges of the work-sheet, said arms hinged 110 to said flanges, springs to hold said arms in position, a rod extending across the platen frame behind the paper shelf, brackets slidably mounted on said rod, and thumb screws securing said table to said brackets.

6. In a typewriting machine, the combination with a roller platen, of a paper guide at the rear of the platen, and extending forwardly thereunder, paper-guiding arms pivoted to said guide and extending for- 130

wardly over the platen, to meet said guide, and springs to hold the arms in effective position; said rear guide and said arms provided with coöperative guides for the 5 opposite side edges of the paper.

7. In a typewriting machine, the combination with a roller platen, of a paper guide at the rear of the platen, and extending forwardly thereunder, paper-guiding arms pivoted to said guide and extending forwardly over the platen, to meet said guide, springs to hold the arms in effective position, and stops to limit the movement of said arms when thrown back to release them from the 10 platen, said springs also effective to hold the arms in released position; said rear guide and said arms provided with coöperative guides for the opposite side edges of the paper.

15 8. The combination with a rotary platen, of a paper-guiding shelf having flanges along its edges to serve as side guides for the work-sheet, and also having a portion curving around forwardly beneath the platen, said curved portion provided with side guides for the work-sheet, and said paper-guiding shelf being adjustable along the platen.

9. The combination with a rotary platen, 30 of a paper-guiding shelf having flanges along its edges to serve as side guides for the work-sheet, and also having a portion curving around forwardly beneath the platen, said curved portion provided with side 35 guides for the work-sheet, and a rod arranged longitudinally of the platen and affording a support along which the paper-guiding shelf may be adjusted.

10. The combination with a rotary platen, 40 of a work-sheet guide mounted at the introductory side of the platen and extending forwardly around the platen, and spaced from the platen to permit the work-sheet to be slid between the platen and said guide to 45 position to be written upon, and lateral guiding means for the work-sheet at each side of said guide to guide the sheet both at the introductory side of the platen, and near the printing line, said work-sheet guide being adjustable along said platen.

11. The combination with a rotary platen, 55 of a work-sheet guide mounted at the introductory side of the platen and extending forwardly around the platen, and spaced from the platen to permit the work-sheet to be slid between the platen and said guide to position to be written upon, lateral guiding means for the work-sheet at each side of said guide to guide the sheet both at the introductory side of the platen, and near the printing line, and a rod upon which the rear portion of said guide is adjustably supported.

60 12. The combination with a rotary platen, 65 of a work-sheet guide mounted at the intro-

ductory side of the platen and extending forwardly around the platen, and spaced from the platen to permit the work-sheet to be slid between the platen and said guide to position to be written upon, lateral guiding 70 means for the work-sheet at each side of said guide to guide the sheet both at the introductory side of the platen, and near the printing line, and a rod upon which the rear portion of said guide is adjustably supported; 75 said guide having means whereby the front thereof is supported by said platen.

13. The combination with a rotary platen, of a work-sheet guide mounted at the introductory side of the platen and extending 80 forwardly around the platen, and spaced from the platen to permit the work-sheet to be slid between the platen and said guide to position to be written upon, and lateral guiding means for the work-sheet at each side of 85 said guide to guide the sheet both at the introductory side of the platen, and near the printing line, said guide also comprising guide-arms extending forwardly over the platen to meet the forwardly extending portion 90 of said guide which extends under the platen.

14. The combination with a rotary platen, of a work-sheet guide mounted at the introductory side of the platen and extending 95 forwardly around the platen, and spaced from the platen to permit the work-sheet to be slid between the platen and said guide to position to be written upon, lateral guiding means for the work-sheet at each side of said 100 guide to guide the sheet both at the introductory side of the platen, and near the printing line, said guide also comprising guide arms extending forwardly over the platen to meet the forwardly extending portion 105 of said guide which extends under the platen, said guide arms pivoted upon said guide, and yielding means for coöperating with said guide and said guide arms to clasp the platen.

110 15. The combination with a rotary platen, of a paper guide or chute comprising an introductory portion arranged in rear of the platen, and also comprising portions encircling the under, front, and top sides of 115 the platen, all of said portions having inwardly curved flanges for guiding the opposite side edges of the work-sheet.

16. The combination with a rotary platen, of a paper chute having an introductory 120 portion arranged in rear of the platen and having paper guiding portions extending forwardly below and above the platen to form a substantially continuous guide for the work-sheet; said introductory portion 125 and said forwardly-extending portions having coöperative guides for the opposite side edges of the paper.

17. The combination with a rotary platen, of a paper chute having an introductory 130

portion arranged in rear of the platen and having paper guiding portions extending forwardly below and above the platen to form a substantially continuous guide for the work-sheet, and comprising lateral guides for the opposite edges of the work-sheet, said lateral guides extending along the introductory portion of the chute, and substantially around the platen to the top thereof.

18. The combination with a rotary platen, of a paper guide or chute curved to conform to the periphery of the platen, and comprising a portion extending upwardly from the introductory side of the platen, said portion having side gages at its opposite edges, and means between the platen and the curved portion of said chute arranged in line with said gages, to gage the forward portion of the work-sheet, said chute mounted for adjustment along the platen.

19. The combination with a rotary platen, of a paper guide or chute curved to conform to the periphery of the platen, and comprising a portion extending upwardly from the introductory side of the platen, said portion having side gages at its opposite edges, means between the platen and the curved portion of said chute arranged in line with said gages, to gage the forward portion of the work-sheet, said forward gaging means being disposed between the platen and the chute, to separate the chute from the platen, and means for yieldingly holding said forward gaging means against the surface of the platen.

20. The combination with a platen, of a chute comprising a main introductory portion mounted at the rear of the platen, and

arms branching forwardly from said main portion above and below the platen; said introductory portion and said arms having coöperative guides for the opposite side edges of the sheet.

21. The combination with a platen, of a chute comprising a main introductory portion mounted at the rear of the platen, and arms branching forwardly from said main portion above and below the platen, and meeting at their forward ends, to form a substantially continuous guide for the sheet; said introductory portion and said arms having coöperative guides for the opposite side edges of the sheet.

22. The combination with a platen, of a chute comprising a main introductory portion mounted at the rear of the platen, and arms branching forwardly from said main portion above and below the platen, certain of said arms being pivoted to said main portion, to permit detachment of the chute; said introductory portion and said arms having coöperative guides for the opposite side edges of the sheet.

23. The combination with a platen, of a chute comprising a main introductory portion mounted at the rear of the platen, arms branching forwardly from said main portion above and below the platen, certain of said arms being pivoted to said main portion, to permit detachment of the chute, and yielding means connected to the pivoted arms to cause them to clasp the platen.

JESSE A. B. SMITH.
